UNITED STATES PATENT OFFICE.

THOMAS I. RANKIN, OF PHILADELPHIA, PENNSYLVANIA, ASSIGNOR TO
ABRAM COX STOVE COMPANY, OF PHILADELPHIA, PENNSYLVANIA,
A CORPORATION OF PENNSYLVANIA.

DESIGN FOR A HEATING-STOVE.

SPECIFICATION forming part of Design No. 35,220, dated October 22, 1901.

Application filed August 16, 1901. Serial No. 72,319. Term of patent 7 years.

To all whom it may concern:

Be it known that I, THOMAS I. RANKIN, a citizen of the United States, residing in Philadelphia, Pennsylvania, have invented and produced a certain new and original Design for a Heating-Stove, of which the following is a specification.

My design for a heating-stove is clearly illustrated in the accompanying drawing, which represents the stove in perspective.

The essential features of the design are, first, the quadrangular shape of the body of the stove, on which is surmounted a heavy crown-section, and, second, the ornamentation of the body and crown.

J is the base of the stove, having scroll-work ornamentation thereon. J' is the ash-pit section, the lower portion of which is ornamented with three medallions in line with scrolls on each side.

J² is the fire-pot section, having quadrangular doors on three sides, each ornamented with vertical bars, the front door having in addition scroll ornamentation.

J³ is the combustion-chamber section, having three open-work doors j, curved and or-

namented at the top with scrollwork. The front door also has spiral scroll ornamentation interlaced with the bar ornamentation. J⁴ is the magazine-section, forming the 30 crown of the stove, supported on the four columns j' of the combustion-chamber section. The panels j² of the magazine-section J⁴ are depressed, as shown, the front panel being ornamented with fan-like scrollwork, while 35 the side panels have a circular ornamentation filled in with open scrollwork. The main portion of the crown is also ornamented with scrollwork and is capped by a dome J⁵ in keeping with the design of the stove. 40

I claim—

The design for a heating-stove as herein described and as illustrated in the accompanying drawing.

In testimony whereof I have signed my 45 name to this specification in the presence of two subscribing witnesses.

THOMAS I. RANKIN.
